UNITED STATES PATENT OFFICE

EDGAR S. STODDARD, OF BERWYN, ILLINOIS, ASSIGNOR TO THE CONOVER COMPANY, OF CHICAGO, ILLINOIS, A CORPORATION OF ILLINOIS

DETERGENT COMPOSITION

Application filed January 18, 1930. Serial No. 421,812.

The present invention relates to an improved detergent composition and a method of utilizing the same, and it particularly relates to an improved detergent composition which is adapted to wash dishes. 5 a minimum and most efficient use of the cleansing agent. Under these conditions it is desirable to utilize a detergent-water composition of special character and quality and to provide such a composition is one of the principal objects of the present invention. 55

Although the present invention is adapted to be utilized in connection with the washing and cleansing of many articles and materials, it will be specifically and very advantageously applicable to the washing and cleansing operations as carried out in dish-washing machines of the spray-projector type. In these machines, a fine spray of the cleansing liquid, which is usually water, containing soap and/or some other detergent, is projected against the surface of the object to be cleansed at the rate of about 2,000 to 3,000 feet per minute, thus causing a considerable impact when the water strikes the object. 10 15 20 25 30 35 40 45 50 55 60 65 70 75 80 85 90 95 100

This impact in addition to the washing action of the water, is effective to loosen and carry away the food and dirt particles adhering to the objects being cleansed.

Spray-projector type dishwashing machines in connection with which the process of the present invention may be very advantageously utilized are more fully shown and described in application Serial Nos. 333,841, 193,414, 262,652, 344,112 and 389,696 filed January 12, 1920, May 23, 1927, March 19, 1928, March 5, 1929, and August 31, 1929, respectively. In these machines the cleansing actions depends upon the operation of a small unencased screw propeller-like impeller, with curved blades, which impeller rotates at a high velocity of the order of 1,000 to 2,000 R. P. M. in the lower part of the tank of the machine. As it turns, the impeller elevates the liquid from its lower screw 40 45 50 55 60 65 70 75 80 85 90 95 100 propeller portions to its upper concave projectors which throw the cleansing liquid at a tremendous velocity directly upon, or into, the objects to be cleansed. Since there are no substantial baffles or deflectors to break the force of the liquid, the total force of the projected mass of liquid is effective for cleansing purposes. Although the velocity of the cleansing liquid is very high, the volume of cleansing liquid is very small, and as a result a very effective cleansing is obtained with

The washing chamber is adapted to be opened either on the top or side, and by means of such opening it may be filled with the objects to be cleansed. In the preferred embodiment of the invention, the dishes, plates and silverware are positioned vertically in the lower part of the washing chamber above the liquid pool and the impeller. In the case of the silverware, the portions which come into contact with the food are positioned uppermost, while in the case of dishes and plates, the concave portions are caused to face the center of the machine either partly or wholly. The upper part of the washing chamber is adapted to contain the deep vessels such as the glasses, cups, deep bowls, etc. These articles are positioned so as to face the impeller or the lower center of the washing chamber. When the dishes have been put into position in the washing chamber, the washing chamber is closed. My invention will be specifically described with reference to the accompanying drawings, in which

Fig. 1 is a cross section of a body of soap 100

incorporated in an outer layer of trisodium phosphate; and

Fig. 2 is a cross section of a capsule containing a body of soap surrounded by a body 5 of trisodium phosphate, these ingredients being separated by a water soluble layer of gelatin.

It is desirable in washing dishes to dissolve an alkaline and/or non-suds-producing detergent in the water first and then after this 10 detergent has dissolved, to dissolve a colloidal or other suds-producing detergent therein. Trisodium phosphate has been found to be one of the most satisfactory detergents 15 to use in the first instance, while soap has been found to be one of the most satisfactory detergents to use in the second instance. These detergents may be added separately, or simultaneously, to the liquid which forms 20 the cleansing medium, but in all cases, provision should be made that the former detergent or substance be dissolved in the water before the latter. This is most readily done in the preferred method of the present invention, in which the soap is added in such a 25 manner that it is coated by, or encapsulated in, trisodium phosphate. One method of accomplishing this is by preparing a soap mixture in a relatively fine state of division 30 which is coated with a substantial layer of trisodium phosphate. This may be accomplished by spray-drying a suspension of soap in a concentrated solution of trisodium phosphate, or comminuted soap particles or flakes 35 may be coated or sprayed with trisodium phosphate. This external layer of trisodium phosphate may be caused to dissolve more slowly and may be caused to form a more coherent coating around the soap particles by 40 the addition of oily, waxy or mucilaginous or other suitable binding materials, such for example, as a mixture of sodium silicate and sodium phosphate. This embodiment of my invention is illustrated in Fig. 1, in which 1 45 represents an inner body of soap and 2 is an external layer of trisodium phosphate.

In another embodiment of the invention, shown in Fig. 2, a double capsule is provided, the interior of which may consist of soap, 50 indicated by the numeral 10 or a material having a similar action, while the exterior may contain trisodium phosphate, indicated by the numeral 20 or a similar material. Both the exterior and interior portions of 55 these capsules should preferably be surrounded by a skin or shell of material which will either disintegrate or dissolve when placed in the cleansing or rinsing liquid. In the drawings, 11 represents a water soluble gelatin layer surrounding the body of the soap, 60 and 12 designates a water soluble gelatin skin which surrounds the outer layer of trisodium phosphate. When the capsules are constructed in this manner, they may be 65 readily prepared and sold to dishwater users,

and they may be proportioned so that putting one or a certain number of the capsules in the cleansing liquid, either before or after its addition to the machine, will suffice to give it the desirable detergent properties. In this last mentioned embodiment of the invention, it has been found most satisfactory 70 to use gelatin shells or coatings which may be insolubilized. Other materials than gelatin may also be utilized, depending upon said 75 solubility in water. Preferably the outer shell should be more readily soluble than the inner shell, so that the trisodium phosphate will have an opportunity to dissolve in the cleansing and rinsing liquid completely before the soap is attacked by the liquid. Gelatin is quite satisfactory, when water is used as the cleansing fluid, because it may be insolubilized in various degrees so that shells of varying solubility may be obtained. In 80 addition, the gelatin when dissolved affects in desirable manner the detergent properties of the liquid. Among other things, it increases the viscosity, the flotation powers of 85 the liquid and the emulsifying qualities 90 thereof. Of course it is obvious that other materials may be used to form the surrounding walls or shells of the capsules, but for reasons which clearly appear, the gelatin has 95 been found to be very satisfactory. When 100 gelatin is used as a separating material, it is preferably used in thickness varying between 1/64th on an inch and 3/64ths of an inch. In other words, it has been found quite satisfactory to use gelatin walls as the separating and casing material approximately 105 1/32nd of an inch in thickness. A satisfactory capsule may be approximately symmetrical in shape with round ends and have a diameter of one inch and a length of 2 1/2 110 inches. These proportions, of course, may be widely varied, according to the use, fluid characteristics and volume and temperature 115 of fluid.

To give an example of the proportioning, 110 in one embodiment of the invention, which is by no means restrictive, it has been found very satisfactory to utilize about one to five tablespoonfuls of a water soluble soap or an alkali metal salt of a high molecular 115 weight fatty acid to every five quarts of cleansing or rinsing liquid. The trisodium phosphate may also be proportioned so that there will be one-half to three tablespoonfuls 120 of this material or a similar alkaline reagent in the external portion of the capsule. The proportions of both soap and phosphate may be varied and are preferably adjusted to the requirements of the local water supply and the amount of water placed in the washing 125 chamber. The figures set forth above are merely to set forth the relative proportions which have been found satisfactory in several instances.

Although as mentioned above, the capsule 130

- may be added in various ways to the cleansing liquid, it has been found satisfactory to add it to the lower part of the washing chamber of the machine so that it will position itself in the cleansing pool which forms in the bottom of the washing chamber and gradually dissolve in such pool. The capsule may also be placed in the entrance pipe in such a position that the liquid will wash over it and gradually dissolve the phosphate and then dissolve the soap. The charge of water or other liquid added to the machine should preferably be too hot to touch. The temperature may be materially over 140° F.
- 15 It usually is not over 210° F. A normal charge for a dishwashing machine will vary between two to fifteen quarts of liquid, depending upon the size of the machine and the actuating device. Although as stated above
- 20 the amount of suds-forming detergent utilized will vary between one to five tablespoonfuls of soap flakes for every five quarts of water, it has been preferred for many purposes to utilize only about one to one and one-half. The concentration of soap should be such that the cleansing liquid has sufficient viscosity and froth to emulsify and/or support the grease and food particles removed from the dishes and to carry them out of
- 25 the machine. The washing and cleansing liquid in the machine may have the consistency of whipped cream. Soapsuds of this consistency reduce the slight noise of the circulating water in the machine.
- 30 35 A particular advantage of the present invention resides in the fact that dishes may be much more satisfactorily cleansed initially with a water treated with an alkaline alkali metal salt such as sodium phosphate before being subjected to a soap cleansing. When the soap becomes dissolved in the liquid, it has a tendency to cushion the cleansing action of the water in certain respects, and for this reason it is very desirable to
- 40 45 have an initial cleansing action which is not cushioned by the soapsuds.
- Although trisodium phosphate is the preferred non-colloidal alkaline reagent and soap is the preferred foaming detergent because of their availability in most households, it is obvious that many equivalent detergents may be utilized. For example, it is possible to utilize other alkaline-reacting salts in place of or in addition to trisodium phosphate. It is also possible to utilize other suds-forming detergents in place of or in addition to soap.
- What is claimed is:
1. A detergent composition comprising a capsule containing soap interiorly and trisodium phosphate exteriorly, the entire capsule being surrounded by a shell of material being disintegrable in water, and the soap and phosphate being separated by an inner shell of similar character.
2. A detergent composition comprising soap surrounded by a shell of trisodium phosphate.
3. A detergent composition, comprising a water soluble capsule containing a body of soap surrounded by a body of trisodium phosphate, the soap and trisodium phosphate being separated by a layer of water soluble gelatin.
4. A detergent composition, comprising a water soluble gelatin capsule containing a body of soap surrounded by a body of trisodium phosphate, the soap and trisodium phosphate being separated by a layer of water soluble gelatin which is less readily soluble than said capsule.
- In testimony whereof I have subscribed my name to the foregoing specification and claims.
